Primary Examiner — Susan Bennett Hattan*Assistant Examiner* — Suzanne E Tisdell(74) *Attorney, Agent, or Firm* — Zagorin Cave LLP; Robert W. Holland(57) **CLAIM**

We claim the ornamental design for a power adapter, as shown and described.

DESCRIPTION

FIG. 1 is a front perspective view of the power adapter comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof;
FIG. 7 is a bottom view thereof;
FIG. 8 is a bottom perspective view thereof; and,
FIG. 9 is a bottom perspective view with a power plug extended thereof.

Evenly-spaced broken lines depict portions of the power adapter form no part of the claimed design. Dot-Dash broken

(Continued)

lines depict claim boundaries that form no part of the claimed design. Areas contained by dot-dash broken lines form no part of the claimed design.

1 Claim, 9 Drawing Sheets
